UNITED STATES PATENT OFFICE.

JAMES A. SPEED, OF SAN FRANCISCO, CALIFORNIA, ASSIGNEE TO NEW SPEED CARBURETER COMPANY, OF SAN FRANCISCO, CALIFORNIA, A CORPORATION OF CALIFORNIA.

CARBURETOR.

1,403,716.

Specification of Letters Patent. Patented Jan. 17, 1922.

Application filed September 14, 1914. Serial No. 861,520.

To all whom it may concern:

Be it known that I, JAMES A. SPEED, a citizen of the United States, residing at San Francisco, in the county of San Francisco and State of California, have invented a new and useful Carburetor, of which the following is a specification.

My invention relates to improvements in carburetors and has for its primary object 10 the securing of a perfect mixture of vaporizing fuel with air to form a perfectly diffused explosive mixture at all speeds of an engine which is being supplied with fluid carburant from said carburetor.

15 The preferred form of my carburetor is free from springs or other elements which would interfere with its perfect automatic control and I provide certain movable parts actuated by the suction caused by the engine 20 requirements for gaseous fuel. The movement of said parts secures a proper relationship between the air supply and the fluid fuel supply forming a perfectly mixed gaseous fuel to meet engine requirements at all 25 speeds, and I combine the parts in my carburetor casing so as to provide against damage from back firing. Further, I arrange them for adaptation to all positions of connecting parts.

30 It is well known that, in the operation of engines being supplied with gaseous fuel from carburetors, it is desirable at different piston speeds of the engine requiring different volumes of mixture, to provide also a 35 different richness of mixture, that is, a different ratio between the fuel and air volumes going to form the gaseous fuel, and to automatically vary these proportions to accommodate different engine piston speeds 40 a proper variation must be secured between the air supply ports and the discharge of fuel into or its rate of entry into the carbureting chamber.

This variation may be obtained by changing 45 the area of the air ports at a varying rate for different engine piston speeds and at the same time varying the rate of the fuel supply at a constant speed, or by varying the area of the air supply ports at a constant

rate and varying the rate of supply of the 50 fuel at a variable rate, or by varying the area of the air ports at an inconstant rate, in either case, securing for any and every given engine piston speed a predetermined definite mixture forming the most efficient gaseous 55 fuel, for that particular engine piston speed.

In the preferred form of my carburetor, and which I have shown in the accompanying figures, I vary the rate of fuel supply 60 automatically at an inconstant but definite rate compared with the rate of variation of air supply. This may be accomplished by using a needle valve in combination with its port through which the fuel is furnished in 65 its passage to the carbureting chamber and making said needle valve of a shape such that for different positions of the movable member there will be a proper variation in said port area as is further indicated in the 70 description and figures below.

Or, by using a needle valve of a straight taper in combination with a hole of constant area such that the area of opening through which the fuel is supplied in its passage to 75 the carbureting chamber varies at a constant rate, but that the fuel is required in said passage to flow to a greater or less elevation before it is discharged into the carbureting chamber and thus is provided variation in 80 the volume of fuel discharged into said carbureting chamber through a constant area, said variation in volume of the fuel being thus secured by the difference in elevation to which the fuel must flow due to the 85 raising or lowering of the discharge ports, and thus furnishing with an air supply varied at a constant rate, the necessary variation of the mixture forming the gaseous fuel for different engine piston speeds. 90

In order to aid in the vaporizing and to thoroughly mix the fuel with the entering air in the carbureting chamber, I prefer to make use of a rotary movement of the inflowing air and gas which is taking place during the 95 mixing process, and thus increase to a considerable degree the efficiency of the resulting gaseous fuel as it is furnished from the

carburetor, especially at high engine piston speeds.

I also provide a means for initially heating the gaseous fuel and means for preventing back firing as more fully described in the specifications and drawings.

Figure 1 is a cross section through my preferred form of assembled carburetor.

Fig. 2 is a side view of my assembled carburetor turned through an angle of 90 degrees from Fig. 1.

Fig. 3 is a plan view of my assembled carburetor.

Fig. 4 is a cross section through $x' x''$.

Fig. 5 is a detail of the mixing vanes.

Figure (3) is a plan view of Figure 5, showing the upper screen partly broken away and the fuel outlets below, and with the pin (p'') dotted in position.

Figure 7 shows in view the upper portion of the carburetor which is shown in section in Figure 1.

In the figures the same numerals refer to the same parts:

(a) is the lower casing to which is connected a fuel supply passage (b) adjustably mounted with respect thereto by the screw (c). By rotating the piece (b) about the screw (c) the passage way (d) may be made to take any position between (d) and (d'). From the chamber formed between (c) and (a) there is a passage way (e) under the control of the valve (f). (e') is a screen to strain the fuel. The valve (f) is carried in a guide by the cap (g) and is actuated by the connecting piece (h) pivoted to the casing (a) and carrying the float (i) within the fuel chamber formed between (a) and the member (j) which forms the inner walls of the float chamber. The member (j) is provided on its circular portion with a suitable passage as at (k) shown in detail in the cross section view Fig. 4.

Passageways (l) admit fuel from the fuel chamber by the passage (k) into the chamber (m, m') in which the dash piston (n) is movable.

In the bottom of the casing (a) is located the needle valve (o) which is vertically adjustable by the head (p) in screw engagement with the nut (q) and being packed against leakage by the gland (r). Mounted with the dash piston (n) is the movable discharge member (s) sliding within the member (j) and carrying fuel ports and discharge outlets and held with respect thereto by the washers ($s s$) and nuts ($s' s'$) and in which is located the passage for fuel (t). Connecting with said passage are a series of discharge openings ($t' t''$).

The movable member (s) is freely movable within a passage way (u) in the piece (j). The air inlet is shown at (v) from which the air passes through the ports (v') in the stationary member (j) and (v'') in

the movable fluid discharge member (s) and by the bars (s'') which carry also the fuel ports (t'), and finds free entry into the carbureting chamber (w).

From the carbureting chamber (w) the gaseous fuel passes by the throttle valve (w') carried on the stem (x) which actuates the throttle valve (w') by foot or hand control in the usual manner and through the usual connections not shown.

When the member (s) is in its lowest position and the ports (v') and (v'') are closed, a vent is formed for any back firing pressure through the ports (y). The throttle valve (w') on the stem (x) is carried in the casing (z) which is rotatable about the vertical axis. The air inlet member (v) may also be rotated to any adjusted position, thus enabling the axis of the throttle valve and the air inlet, or either of them, to be aligned with the connections for the carburetor, by rotation taking place around the joints (z') or (z'').

The air passage (v) in its rotated position is clamped by the collar (a') and screw (b'), thus enabling the air inlet to be turned in the direction of motion to facilitate air entry or to connect it with a suitable supply of warm air as, for example, from around the engine discharge pipes or some other heated portions of the engine. The carburetor may be quickly disconnected by removing the screw (b'), loosening the collar (a') and disconnecting the screw (c) thus quickly exposing all the working parts.

The piston (n) I arrange with a port (n') controlled by the valve (n'') having a small opening (e'), said valve being held in place by the bar (f'').

Within the mixing chamber I provide dispersion or guide vanes ($w w'$) Fig. 5, against which the inflowing fluid is diverted to cause a helical movement thereof to facilitate the mixing and secure a thorough incorporation with the said air of the vaporizing fuel during this vortex movement, and where heavier fuels are used in order to further thoroughly incorporate the volatilized fuel into a homogenous gaseous fuel with the air, there may be provided the screen (w'').

The operation of my carburetor is as follows:

Fuel being admitted through the passage-way (d) finds entry through the passage-way (e) into the chamber ($a a'$) filling said chamber to such a point that the float (i) is raised, depressing the valve (f) and closing the port (e). The fuel has in the meantime passed through the passages (l) and (k) into (m) and through (n') into (m') filling completely the space around the dash piston (n). It is obvious that the float (i) will upon fuel being withdrawn descend, opening the valve (f) and admitting the requisite additional fuel so as to keep the proper level in the float chamber ($a a'$).

This float and its valve is well known and forms no part of my claims. The movable discharge member (s) and the piston (n) are now in their lowest positions. Upon 5 starting the engine, the suction produced by the movement of the piston within the engine causes an upward movement of the member (s) and the piston (n). This is due to air pressure against the plate (y') supplied through the port (y). 10 If the movement of said piston is rapid, there will be a restraint put upon the movement of the member (s) by the slow passage of liquid fuel through the small hole 15 in the valve (n'') in the piston (n). This retardation of the movement of member (s) is for the purpose of accelerating the flow of fuel through the ports (t' t') due to momentary relatively increased suction. 20 This retardation of the member (s) is however only momentary as it quickly rises and as the engine speed increases, to the proper position for the admission of the proper amount of air through the registering passages (v, v') and (v'') to supply the demands of the engine. As the member (s) 25 is advanced upwardly, the opening provided by the passage way (t) around the needle valve (o) is increased in area providing a proper increased amount of fuel to be discharged through the said passage (t) and ports (t' t') with the air being admitted through the registering ports (v', v'') into the carbureting chamber (w). 30 The degree to which the member (s) will rise, will therefore be determined by the rate of flow of gaseous fuel demanded by the piston speed of the engine, and the mixture of gaseous fuel will be determined by 35 the registering passages (v' v'') for the air and area of the passage (t) around the valve (o) and also by the height to which the fuel must rise from the level of the fuel in the float chamber (a a) to the outer 40 surfaces of the ports (t' t') as it is a liquid until its arrival at the outlets of said ports and of very much greater density than in its gaseous form when it is discharged into the carbureting chamber (w). It will thus be 45 seen that the fuel having to rise to a greater elevation before being discharged into the carbureting chamber (w) from the ports (t' t') will result in a less differential pressure to force the fuel through the passage 50 (t) in its upper position in combination with valve (o), and secondly, it will be seen that as the movable member (s) is raised by increased demand from the movement of the pistons in the engine, there will be an 55 increase in the rate of fuel flow through the ports (t' t') because of the larger opening provided by the passage (t) around the valve (o), but that this increase will not be at a constant rate in proportion to the 60 movement of said member (s) because of the 65

retardation occasioned by the increased height to which the liquid fuel must be drawn before it discharges through the ports (t' t').

During the movement upward of the member (s) the registering air passages (v', v'') have been increasing proportionally to said movement. The result will therefore be that on the slow increasing of the piston speed of the engine to which the carburetor is connected there will be an increase in volume directly proportional to said demand without any throttling effect of springs or other means and that the gaseous fuel will not be quite so rich in hydro-carbon as at the lower piston speeds, and that this is independent of the position of the throttle valve (v v'), the gaseous fuel thus automatically being obtained of the proper degree of richness for every piston speed. 80

Upon a retardation of engine piston speed, the member (s) will descend, closing off or reducing the air inlet through the registering passages (v' v') to the new speed requirement and simultaneously closing to a greater degree the passage (t) by its closing over the valve (o). 90

In order that the engine shall properly accelerate on a quick opening of the throttle valve (v') the upward movement of the member (s) is momentarily restrained as previously described by the piston (n) thus permitting momentarily a richer gaseous fuel to be supplied to the engine facilitating acceleration. 100

In the event of back firing, the movable member (s) descends to its lowest position and discharges the burning gases through the passage ways or clearance around its walls. 105

At any demand made by the engine for gaseous fuel, the inflowing air during the early period of mixing has attained a rotary movement against the vanes (w w) and a thorough incorporation with the volatilizing fuel from the ports (t' t'), and with heavier fuels, a still further intimate admixture through the screen (v''), in all cases providing a thoroughly homogeneous gaseous fuel on its discharge from the carburetor. 110

Upon the engine demanding gaseous fuel, the movement of the member s is permitted by the chamber in which it moves having communication with the air through the passage ways (y), thus preventing the formation of a vacuum therein and allowing a free movement of the movable member or fuel elevator s. 120

Special attention is directed to the valve n'' in the dash piston (n). I form this valve n'' with a small passage way (e') so that upon an effort on the part of the fuel elevator or movable member rise under the action of suction from the engine, the liquid 125

contained in the chamber (m') must pass into the chamber (m), and while it is doing so, the movement of the fuel elevator s is being restrained by the dash piston (n).
5 The small hole (e') provided in the said valve allows the escape from the compartment (m') into (m) thus determining the rate of elevation of the movable member. It is to be noted that with lighter fuels and
10 higher temperatures, the rate of movement in an upward direction of the dash piston (n) may be faster under a given suction demand than with heavier fuels and lower temperatures, and that this condition is of
15 great advantage in adapting my carburetor to varying atmospheric conditions and qualities and characteristics of fuels because a greater restraint is to be placed upon the upward movement of the fuel elevator or
20 movable member s where the fuel is heavy or cold so as to attain the necessary increased carbon content by increased suction of the fuel during periods of engine acceleration. I also provide an auxiliary air
25 supply as indicated at (o') Figs. 1 and 3, (o') being air passage ways into the passage way (v), (o'') being a shutter registering with said passage ways and (o''') a lever connection with the throttle valve spindle (x) engaging during the latter portion
30 of the throttle valve movement with the shutter pin (y) projecting through the slot in plate (y') which may be formed right or left, or both, to admit into the passage way
35 (v) an increased supply of air at a lower temperature than that ordinarily being supplied through the passage way (v), thus preventing too great a heat being conveyed to the carburetor parts which would otherwise result in too great an expansion of the gaseous mixture before its entry into the motor. The movable member or fuel elevator is provided with a surface plate or disc
40 (y') against which atmospheric pressure is available through the passage (y) to cause the action of the movable member upon suction being produced by the engine. This plate is provided with a hole sliding over the pin (p''). The pin p'' is provided to
45 engage with a hole in the movable member or fluid elevator. Said pin is curved or may be set up at an angle from the vertical, see Figures 5 and 6, thus causing a helical movement of the fuel elevator as it is raised. It will thus be seen that the air ports may, through the cylindrical surface of the movable member, be covered or uncovered at a varying rate compared with the upward movement of the fuel elevator. It will thus
50 be seen that, by the needle valve in the cylindrical stem of the elevator, the air ports in the cylindrical surface of the fuel elevator and its surrounding guide surface and the elevation to which the fuel must be
55 drawn by the suction of the engine above

the surface of the fuel in the reservoir, there are provided exact proportions of air and fuel to the carbureting chamber to correspond with each and every engine piston speed and that the carburetor will feed at
70 every engine speed, the requisite gaseous fuel of highest efficiency. Said feeding is dependent upon the position of the fuel elevator and therefore upon the piston speed of the engine and independent of the separately operated throttle valve, the movement of said throttle valve being merely to limit the upward movement of the fuel elevator. Upon the throttle valve being opened, the added suction placed upon the fuel elevator
75 will cause more fuel to feed and the fuel elevator will rise on an increased suction demand of the engine as fast as the engine can increase its speed and will then maintain during its high speed a proportionately
80 higher level.

In addition to the improvements enumerated above there are others incorporated in my carburetor which, however, are made the subject of separate applications by me; see particularly issued Patents No. 1,145,172 and No. 1,200,039, and my copending application Serial No. 244,054, filed July 9, 1918.

Having thus described my invention, I claim:—

1. In a carburetor, a fuel reservoir, a float in said fuel reservoir controlling an admission valve thereto, a movable discharge member for discharging fuel from said reservoir into a carbureting chamber at different elevations above the fuel level in the reservoir according to the demand of the engine for fuel, air passages controlled by said discharge member, said passages communicating with a primary air inlet and a secondary air inlet, said secondary inlet being adjustable.

2. In a carburetor a movable fuel discharge member adapted to discharge fuel at varying elevations with respect to the fuel surface in a reservoir, a fuel reservoir connected therewith, a dash chamber and piston movable therein adapted to restrain the movement of said movable member during periods of greater demand from the carburetor, said movable member arranged with a cylindrical surface having ports therein and registering with a corresponding cylindrical surface having ports therein, said ports controlling the admission of air.

3. In a carburetor, the combination with the casing containing the mixing chamber, of an automatic air valve controlling the admission of air to said mixing chamber, co-operating means variably restricting the flow of the liquid fuel, and a dash pot for retarding the opening movement of said valve, permitting the unresisted closing thereof.

4. A carburetor including a fuel reservoir,

a suction controlled automatic air valve tending to close by the action of gravity, fuel discharge means carried by the air valve and adapted to discharge fuel at varying elevations with respect to the fuel surface in the reservoir, means controlled by the movements of the air valve for variably restricting

the flow of fuel, and means for resisting the opening of the air valve and permitting the unresisted closing thereof.

JAMES A. SPEED.
